UNITED STATES PATENT OFFICE.

HILDA BROADWOOD, OF MOBILE, ALABAMA.

DESIGN FOR A HEARTH BROOM.

Application filed February 15, 1927. Serial No. 20,772. Term of patent 7 years.

To all whom it may concern:

Be it known that I, HILDA BROADWOOD, a citizen of the United States, residing at Mobile, in the county of Mobile and State of Alabama, have invented a new, original, and ornamental Design for Hearth Broom, of which the following is a specification, reference being had to the accompanying drawing, forming part thereof.

I claim:

The ornamental design for a hearth broom, as shown.

HILDA BROADWOOD.
